UNITED STATES PATENT OFFICE.

VIRGIL A. SCOFIELD, OF COCHISE, ARIZONA.

MOISTENING DEVICE FOR ENVELOPS.

1,246,793.

Specification of Letters Patent. Patented Nov. 13, 1917.

Application filed November 17, 1915. Serial No. 62,005.

To all whom it may concern:

Be it known that I, VIRGIL A. SCOFIELD, a citizen of the United States, residing at Cochise, in the county of Cochise and State 5 of Arizona, have invented certain new and useful Improvements in Moistening Devices for Envelops; and I do hereby declare the following to be a full, clear, and exact description of the invention, such as will enable others skilled in the art to which it 10 pertains to make and use the same.

The primary object of this invention is to provide a simple, cheap, durable and efficient envelop moistener and sealer, of such 15 construction that the operation of moistening and sealing can be conveniently and expeditiously performed.

Other objects will appear and be better understood from that embodiment of my 20 invention of which the following is a specification, reference being had to the accompanying drawings forming a part thereof in which:

Figure 1 is a top plan view of the combined moistener and sealer,

Fig. 2 is a front elevation thereof,

Fig. 3 is a longitudinal section through the moistener,

Fig. 4 is a transverse section through the 30 moistener and sealer,

Fig. 5 is a perspective view of the presser plate for the moistener, and

Fig. 6 is a perspective view of the presser 35 view of the presser plate detached from the moistener.

Referring to the drawings in detail, the numeral 1 designates a housing, of rectangular configuration and having the top thereof open. The rear wall of the housing has its upper edge extended upwardly to 40 provide a wall 2, said wall being offset at a point above the housing 1, as at 3, said offset portion having formed therein a pair of spaced slots 4—4, which are located adjacent the opposite ends of the wall, the 45 terminal of the wall being extended vertically above the offset portion 3, as shown at 6.

Removably positioned within the housing 1 is a receptacle 7. This receptacle is of 50 rectangular configuration and has the top and bottom thereof open, and has its side and end walls arranged in spaced relation to the respective side and end walls of the housing 1, as shown in Figs. 3 and 4 of the drawings.

Removably mounted upon the upper end

of the receptacle 7, is a bed-plate 8. This bed-plate 8 has an opening 9 therein, communicating with the interior of the receptacle and by means of which water can be 60 poured into the receptacle. The bed-plate 8 has a marginal depending flange 10 thereon, which extends into the space between the receptacle and the housing, spaced from the walls of the receptacle and the housing, as 65 shown in Figs. 3 and 4 of the drawings. The bed-plate 8 has associated therewith liquid absorbing fabric 11. This liquid absorbing fabric 11 covers the entire upper surface of the bed-plate 8 and has extensions 12—12 formed thereon, which engage under the depending flange 10 and extend into the receptacle and are secured to each other by means of a hook and eye 13 and 70 14. An extension 15 extends from the rear edge of the fabric 11 and engages around the rear side of the flange 10 and over the rear wall of the receptacle, and terminally extends into the receptacle so as to admit of the water or other liquid within the receptacle being fed to the fabric on the bed-plate, by capillary attraction. The fabric 75 11 has also formed thereon at its forward longitudinal edge, a pair of depending sections 16 which extend into the space between the front walls of the receptacle and housing, as shown in Fig. 4 of the drawings. The fabric 11 is provided with a cutaway portion 17 providing an opening which registers with the opening 9 so as to admit of 80 85 the filling of the receptacle 7 with liquid.

Operable against the bed-plate 8 and the absorbent material 11, is a presser plate 18. The presser plate 18 is of substantial rectangular configuration and has a manipulating member 19 thereon. The rear longitudinal edge of the presser plate 18 has a ledge 20 formed thereon and projecting upwardly from the upper edge of the ledge 20 95 is a pair of spaced guide members 21 which 100 slidably extend through the slot 4 in the offset portion 3 of the wall 2 and have their upper terminals bent downwardly as at 22. A coil spring 23 is secured to the upper end of the wall 2, and centrally thereof, and 105 has its opposite ends extended upwardly in diverging relation and terminally engaged under the downwardly bent terminal 22 on the guide 21, as shown in Figs. 2 and 4 of the drawings. The spring 23 serves to 110 return the presser plate 18 to normal inoperative position, after the same has been

operated. The pressing device, designated by the numeral 25 as an entirety, is positioned exteriorly of the housing 1 and at the front wall thereof and includes a rectangular shaped bed-plate 26, having a vertical wall 27 formed on the rear longitudinal edge thereof, said wall having its upper end deflected inwardly, as at 28, and provided with a pair of spaced longitudinal slots 29.

10 The wall 27 has a vertically disposed hook 30 formed centrally thereon, the bill 31 of which is adapted to detachably engage over the upper edge of the front wall of the housing 1 and to lie between the front wall of

15 the housing 1 and the front wall of the inner receptacle 7.

Operable against the bed-plate 26 is a presser plate 32 having a manipulating handle 33 formed thereon. This presser plate 20 is of rectangular configuration and has its rear longitudinal edge provided with vertically disposed guide strips 34 slidably extending through the longitudinal slots 29 in the deflected end of the wall 27 and have 25 their terminals bent inwardly, as at 35. The inner face of the wall 27 has a coil spring 36 associated therewith, the opposite ends of which spring are extended in diverging relation to each other and terminally engage 30 under the bent terminal 35 of the guides 34. The spring 36 serves to return the pressure plate 32 to normal position after the same has been operated.

The presser plates 18 and 32 are each 35 formed of a blank of material folded upon itself to provide a superposed flap, the rear edge of the upper flap being bent upwardly and cutaway at spaced points to provide the guide strips at the rear edges of the 40 presser plate. Likewise, the bed-plate 26 of the sealing device is also formed of a single blank of material folded upon itself so as to provide superposed flaps, and having the rear end of the uppermost flap extending 45 upwardly to provide the wall 27, the said wall being cut away to provide the vertically disposed hook 31.

In use, the receptacle 7 and the space between the receptacle 7 and the housing 1 are 50 filled with liquid, the extensions 15 and 16 of the absorbent strips of material 11 drawing the liquid upwardly, resulting in the saturation of that portion of the absorbent material which covers the bed-plate. When

it is desired to moisten the flap of an envelop, the gummed surface of the flap is placed on the absorbing material 11 on the bed-plate 8 and the presser plate 18 lowered, causing the flap of the envelop to be pressed tightly into engagement with the absorbent 60 material, resulting in the moistening of the gummed surface of the envelop flap. When the presser is released from the presser plate, the spring 23 will return the presser plate 18 to normal position. After the 65 gummed surface of the envelop flap has been moistened, and the flap folded to closed position on the envelop, the envelop is placed on the bed-plate 26 of the sealing device and the presser plate 32 lowered into engagement with the envelop, so as to cause the flap to adhere to the envelop. When the presser is released from the presser plate 26, the spring 36 will return the plate to normal position.

Having thus described my invention, what I claim as new is:—

1. A device of the class described comprising a housing, a receptacle located within the housing, a bed plate positioned on the receptacle, liquid absorbing material associated with the bed plate and extending into the receptacle, one of the walls of the housing being extended above the bed plate and provided with slots, a presser plate operable 80 against the bed plate, guides carried by the presser plate and slidably mounted in the openings in the mentioned wall of the housing.

2. A moistener including a bed plate, a 90 wall located in rear of the bed plate and having its upper end provided with slotted offset portions, a presser plate operable against the bed plate, vertical guides mounted on the presser plate and slidably through 95 the slot in the offset portion and having their upper terminals bent downwardly, and a spring associated with the wall and having its opposite ends engaging under the downwardly bent terminals of the sides, for 100 the purpose specified.

In testimony whereof I affix my signature in presence of two witnesses.

VIRGIL A. SCOFIELD.
